 River Raisin Paper Company, Monroe, Mich., a
 corporation of Michigan

Application June 12, 1937, Serial No. 147,910

3 Claims. (Cl. 248—174)

This invention relates to a display stand adapted for use in displaying and advertising merchandise, and more particularly to a stand of the type mentioned that is formed of sheet material, such as cardboard or the like.

One object of the invention is to provide a stand of the type mentioned which is folded out of only two rectangular sheets of material with a minimum number of operations and a minimum waste of material.

Another object of the invention is to provide a stand which can be collapsed into a flat package for shipment and can be assembled without the use of any fastening means.

Another object of the invention is to provide an improved and simplified means for supporting a tray or shelf in a display cabinet of the type mentioned.

Another object is to provide a stand having an auxiliary display shelf formed in one wall thereof for carrying supplemental displays of goods.

Other objects and advantages of the invention will become apparent from the following specification, the accompanying drawings, and the appended claims.

In the drawings:

Figure 1 is a perspective view of one form of the assembled stand;

Fig. 2 is a perspective view of the main body portion of the stand with the shelf element removed; parts being broken away to show the interior construction;

Fig. 3 is a section taken on the line 3—3 of Figure 1;

Fig. 4 is a perspective view of the shelf element removed from the main body portion of the stand;

Fig. 5 is a view of the shelf element showing an alternative manner in which it may be assembled in the stand;

Fig. 6 shows a modified form of the stand, in which there is embodied an auxiliary display shelf;

Fig. 7 is a perspective view of the main body of the stand shown in Fig. 6 with the shelf element removed to show the interior construction;

Fig. 8 is a section taken on the line 8—8 of Fig. 6; and

Fig. 9 is a perspective view showing the shelf element removed from the assembly.

Referring particularly to Figures 1 and 2, the main body portion of the stand is formed of a single rectangular sheet of deformable material,

such as cardboard or the like, which is divided by parallel crease lines into four initially rectangular side panels 10, 11, 12 and 13. The side panels 10 and 12 are provided with suitable tabs 14 and 15, as best shown in Figure 2, which are secured to the panel 13 in any desired manner, as by staples, to form a box-like structure having four rectangular sides and an open top and bottom. It will be noted that this box-like structure may be collapsed into a flat package for shipment purposes or storage without disconnecting the adjoining edges of panels 10 and 13.

Each of the panels or sides of the box structure is provided with three parallel crease lines 16, 17 and 18, extending entirely across the sides of the box and parallel to the bottom edge 19 thereof, thereby forming two horizontal panels 20 and 21 upon each side or main panel of the stand. As best shown in Figs. 2 and 3, the panels 20 and 21 may be folded inwardly of the stand to provide a double folded inwardly extending horizontal flange entirely around the periphery of the stand when the latter is opened up to the assembled positions shown in Figs. 1 and 2. The edges of the panels 20 and 21 are relieved or cut away at 22 and 23 to prevent interference when the panels 20 and 21 are folded inwardly. It will be observed that panels 20 and 21 may be swung into the planes of the main body panels 10, 11, 12 and 13 when the stand as a whole is collapsed for purposes of shipment or storage.

The top edges of the panels 10 and 12 are folded inwardly along a diagonal line, and the resulting triangular flaps 25 and 26 are permanently secured to the panels 10 and 12, respectively, in any suitable manner, such as by stapling. This provides downwardly inclined top edges 27 and 28 for the panels 10 and 12, which edges are of greater strength and improved appearance over correspondingly inclined edges formed by cutting away portions of the panels 10 and 12. The top edge of panel 11 is provided with a crease line 29 connecting the lowest portions of the inclined top edges of panels 10 and 12 to form a flap indicated generally at 30. The flap 30 is provided with a parallel crease line 31 and a projecting tongue 32. When flap 30 is folded outwardly of the box, as best shown in Figs. 1 and 3, the tongue 32 is adapted to project into a slot 33 formed in panel 11 to provide an inclined panel 34 upon which suitable advertising or printed matter may be placed. It will be noted that when the stand is folded flat, the tongue 32 on the flap is withdrawn

from slot 33 and the flap as a whole is placed in the same plane as panel 11.

The stand is completed by the addition of a shelf element shown as a whole in Fig. 4. This element is also formed of a single rectangular sheet of cardboard or the like and is creased transversely substantially midway of its ends at 35 to provide a back panel 36 and a shelf panel 37. These panels 36 and 37 are stiffened at 10 bent-over flanges 38, 39, 40, 41 and 42. It will be noted that the flanges 38 and 39 on the back panel 36 do not extend to the top of this panel, with the result that there is provided on the back panel 36 outwardly extending projections 15 43 and 44 adapted to extend beyond the sides of the main body portion when the shelf element is assembled, as best shown in Fig. 1. The flanges 39 are cut from the back panel 36 at their upper edges along the diagonal lines 45 and 20 46. This leaves downward projections on the outwardly extending portions 43 and 44 which may be cut away, if desired, along the lines 47 and 48 indicated in Fig. 4.

The shelf element is inserted within the open 25 upper end of the main body portion. It snugly fits the body portion and rests upon the inwardly extending flanges formed by panels 20 and 21, as best shown by Fig. 3. As shown in Figs. 1 and 4, the flanges 40 and 41 on the shelf panel 30 37 are bent upwardly with the result that the panel 37 rests directly upon the panels 20 and 21. In this position, a slot 50 formed in the flange 42 of the shelf element is in alignment with the slot 33 in the front panel 11, and is 35 therefore adapted to receive the tongue 32, as best shown in Fig. 3.

The shelf element is adapted for positioning at different elevations within the main body portion by reason of the fact that flanges 40 and 40 41 of the shelf panel 37 may be turned downwardly, if desired, as shown in Fig. 5, in which event the flanges 40 and 41 will rest upon the inturned flange of the main body portion formed by panels 20 and 21 and thus support the shelf 45 panel 37 at a higher elevation than that shown in Figs. 1 and 3. This is of advantage when the merchandise to be displayed comprises relatively small articles. In order to accommodate the tongue 32 when the shelf element is positioned in its elevated position, there is provided an auxiliary slot 51 in the flange 42. It will be noted that no changes in the structure of the stand or shelf element are required to adjust the elevation of the shelf element.

55 When the shelf element is assembled, it will be noted that it holds the main body portion of the stand in its rectangular boxlike shape and that the weight of the merchandise carried by the shelf element will hold the two flange panels 20 and 21 in face to face contact with each other, as shown in Figures 1 and 3. Accordingly, it is unnecessary to provide any fastening means for securing the panels 20 and 21 in their face to face position. Preferably the lower side 60 edges of the panel 36 of the shelf element snugly fit the interior of the boxlike body portion with the result that the back panel 36 is frictionally held in a position shown in Figure 1, in which position the upwardly and outwardly projecting portion of the back panel is adapted for the 65 reception of printed or other advertising matter.

In Figures 6 to 9, inclusive, is shown a modified form of the box wherein there is incorporated an auxiliary display shelf. In this form of the invention, the main body portion of the box is

identical to that previously described except that there is provided in the upper portion of the back panel 13 of the main body portion a pair of triangular ears 60 and 61, which may be bent inwardly from the back panel. Ears 60 and 61 are 5 provided with tongues 62 and have flat horizontal top edges 63, as best shown in Figures 7 and 8.

The shelf element in this form of the invention is best shown in Figure 9, wherein it will be seen that it comprises a bottom panel 64 having flanges 10 65, 66 and 67, corresponding to the flanges 40, 41 and 42 of the form of the invention shown in Figures 1 to 5. In this case, however, the back panel 70 is provided with three parallel horizontal crease lines 71, 72 and 73, defining four 15 panels 74, 75, 76 and 77. If desired, flaps 78 and 79 may be provided at the edges of the back panel 70 above the crease line 71, but these flanges or flaps are not extended below the crease line 71, as in the previous modification. 20

When the shelf element is assembled within the main body portion of the stand, the supporting panel 64 rests directly upon the inturned flange formed by panels 20 and 21, as in the previously described embodiment of the invention, and the 25 back panels 74 and 77 rest against the main body panel 13. The back panels 75 and 76 of the shelf element, however, as best shown in Figure 8, bear against the edges of the triangular ears 60 and 61, the panel 76 resting upon the 30 horizontal top edge 63 of these ears. It is apparent, therefore, that the panel 76 forms a horizontal auxiliary display shelf and is supported in position by means of triangular ears 60 and 61. The back panel 75 is preferably provided 35 with suitable slots 80 for the reception of the tongues 62 on the triangular ears 60 and 61. When the stand is assembled, these ears may be bent over to assist in retaining the back panel 40 in position.

It will be observed that in accordance with both forms of the invention, the entire stand is formed of two rectangular blanks, all portions of which that are required to be connected together at all, are permanently connected prior to shipment. 45 Nevertheless, the blanks may be shipped in a collapsed and flat condition and thereafter assembled to final form without the necessity of making any further connections between the parts thereof. Moreover, the resulting assembled stand 50 is quite sturdy. The shelf element holds the main body portion in a full open position, and the weight of the merchandise displayed holds the shelf in position and the top and bottom portions of the main body collapsed into contact 55 with each other. Accordingly, the stand may be disassembled and collapsed to a flat condition at any time without in any way injuring it or marring its appearance.

In addition to the above, it will be noted that 60 all of the exposed top edges of the body are smooth folded edges and that the inclined surface panel 34 and the back panels 36 or 77 of the shelf element provide exceedingly effective locations 65 for displaying advertising matter.

In addition to the above, the form of the invention shown in Figures 1 to 5, inclusive, has the advantage that the shelf element may be adjusted to any desired height and the form shown 70 in Figures 6 to 9 embodies an exceedingly simple, yet sturdy and effective auxiliary display shelf in combination with the back panel of the shelf element. The stand as a whole is exceedingly simple and inexpensive to manufacture and as- 75

semble, and can be made with a minimum waste of material in view of the fact that all component parts are formed out of two substantially rectangular sheets of material.

5 While only two forms of the invention are shown and described, it is apparent that others are available within the spirit of the foregoing specification, the accompanying drawings, and the appended claims.

10 What is claimed is:

1. A display stand comprising a boxlike body portion formed of four panels of sheet material connected at their edges, each of said panels having portions intermediate their ends collapsed inwardly in substantially the same transverse plane in a double fold to provide inwardly projecting flanges, the edges of the flanges adjacent the creases thereof being cut away to prevent interference therebetween, and a partition member 15 in the box structure resting on said flanges.

2. A display stand comprising a single sheet of bendable material formed into a closed box structure having four side panels with parallel connecting edges whereby the box structure may be collapsed into a flat condition without disconnecting the adjoining edges of the panels, each of said side panels being provided with three parallel crease lines disposed beneath the top edges of said side panels, the respective lines on

each panel lying in the same transverse plane as the corresponding lines in the other panels whereby the material intermediate the outer crease lines may be folded inwardly into double flanges, the edges of said panels adjacent the 5 foldable portions being cut away to prevent interference therebetween, and a partition adapted to rest upon said flanges.

3. A display stand comprising a boxlike structure open at the top, means in said box structure 10 and below the top edge thereof for supporting a shelf, and a shelf element formed of deformable sheet material having a panel adapted to fit the interior of the box structure and rest on said means, and having a second panel connected to 15 the first panel at one edge and projecting upwardly adjacent one side wall of said box structure, said second panel having a plurality of parallel horizontal crease lines and being bent at 20 said lines to form an auxiliary display shelf, and means complementary in shape to the shape of the auxiliary display shelf on one side of said box structure for engaging and thereby supporting said auxiliary display shelf, said last named 25 means including a tongue which extends through a slot in one wall of the auxiliary shelf to fix said auxiliary shelf in position.

LAWRENCE W. REAUME.
